UNITED STATES PATENT OFFICE.

GOTTFRIED E. SCHWEIZER, OF BRIDGEPORT, CONNECTICUT.

DESIGN FOR A REAR-END SIGNAL DEVICE FOR AUTOMOBILES.

50,921.

Specification for Design.

Patented June 12, 1917.

Application filed January 30, 1917. Serial No. 145,536. Term of patent 3½ years.

To all whom it may concern:

Be it known that I, GOTTFRIED E. SCHWEIZER, a citizen of the United States, residing at Bridgeport, county of Fairfield, and State of Connecticut, have invented a new, original, and ornamental Design for a Rear-End Signal Device for Automobiles, of which the following is a specification, reference being had to the accompanying drawings, forming part thereof, in which—

Figure 1 is a face elevation and Fig. 2 a side elevation, showing my new design.

I claim:

The ornamental design for a rear end signal device for automobiles as shown.

GOTTFRIED E. SCHWEIZER.

Witnesses:

F. W. SMITH, Jr.,
M. T. LONGDEN.
